UNITED STATES PATENT OFFICE.

JAMES S. WILSON, OF CHELSEA, MASSACHUSETTS.

FLEXIBLE CONDUIT.

No. 880,850.

Specification of Letters Patent.

Patented March 3, 1908.

Application filed May 20, 1907. Serial No. 374,604.

To all whom it may concern:

Be it known that I, JAMES S. WILSON, of Chelsea, in the county of Suffolk and State of Massachusetts, have invented certain new and useful Improvements in Flexible Conduits, of which the following is a specification.

This invention relates to an improvement in flexible conduits, and particularly, that class shown in the patent to Herrick, No. 10 456,271, dated July 21, 1891, and consists in securing the fiber convolutes forming the lining at different points, to the body of the tube to prevent the fiber being pulled out.

Figure 1 is a detail view, showing a section of a conduit constructed in accordance with my invention, a part of the conduit being broken away, in order to show the means for securing the spiral fiber to the body of the tube. Fig. 2 is a view similar to Fig. 1, showing a somewhat different arrangement of the fastening members. Fig. 3 is a cross-sectional view, on line 3—3 of Fig. 2, showing the arrangement of the fastening member with the convolutes of the spiral and the body of the tube. Fig. 4 is a detail view of a piece of the spirally wound fiber strip with the fastening member arranged therein, the edges of the strips being separated. Fig. 5 shows a way of passing the fastening devices through the convolutes of the fiber strip, the bending of the tube in the form shown forcing the fiber strip against the wall of the tube, so that a straight needle or tool will penetrate the fiber.

The same reference characters indicate the same parts in all of the figures.

The specific form of tube shown in the drawings is that shown in the patent to Herrick, No. 456,271, dated July 21, 1891. I do not wish, however, to be understood as limiting my invention to that specific form of tube, my invention being applicable to all forms of tubing employing a core or lining made up of spirally wound strips of fiber, or other material. I take the Herrick form of tube merely as an illustration. In the use of the Herrick form of tube and all flexible conduits whose inner walls are made up of a strip of fiber wound spirally, no means other than the cementing of the

spiral to the walls of the tube have been devised to prevent the pulling out of the fiber strip, either accidentally or purposely. This has proved a great defect and many expedients have been attempted to overcome 55 this defect, but without success.

In the drawings, the tube is shown as composed of a strip 1, of fiber, wound spirally on itself. Upon this strip is applied what is called a friction tape 2, which serves to hold 60 the convolutes of spiral fiber 1, together in the form of a tube. Upon the tape 2 is applied a covering 3, in any suitable way, the covering 3, here shown, consisting of threads of cotton interwoven.

4 represents a thread or other fastener of non-conducting material passed through the wall of the tube and under and around certain convolutes of the fiber strip 1, as in Fig. 1, or continuously back and forth along one 70 side of the tube through the body of the tube and between or through the convolutes of the strip 1, as in Figs. 2 and 3, or through the body of the tube and one or more of the convolutes of the strip 1, as in Figs. 4 and 5. 75 The fastening member 4 may be of thread, or any other preferred means. I have not attempted to show all of the ways in which this fastening member may be applied. A tube constructed as described, wherein the convolutes of the tape 2 are secured to the body 80 of the tube at different points, prevents the withdrawal of the strip 1 from the tube.

While in the drawings I have shown the fastening member passing entirely through 85 the body of the tube, yet, manifestly, my invention embraces like constructions where the fastening member connects the convolutes of the tape to the wall of the body of the tube in any way. The fastening member 90 may be passed through the body of the tube and the strip 1, by any suitable tool, operated by hand or by any suitable machine.

In Figs. 4 and 5, the symbol 4 indicates not 95 only the thread, but also the path taken by the tool by which the thread is inserted.

Having thus explained the nature of my invention and described a way of constructing and using the same, though without at- 100

tempting to set forth all of the forms in which it may be made, or all of the modes of its use, what I claim and desire to secure by Letters Patent is:—

5 A flexible conduit comprising an inner wall composed of successive turns of a strip of material, forming a tube, a body of any suitable material, applied to and surrounding said tube, and a fastening member or mem-

bers securing said tube at different points to 10 said body.

In testimony whereof I have affixed my signature, in presence of two witnesses.

JAMES S. WILSON.
